Fig. 1

Fig. 5

Fig. 5

FIGURE 1 is a top plan view of a loading ramp for vehicles and the like, showing my new design;

FIGURE 2 is a fragmentary, top plan view of the loading ramp on an enlarged scale;

FIGURE 3 is an enlarged, fragmentary, transverse sectional view of the loading ramp, taken on the line 3-3 of FIGURE 2;

FIGURE 4 is an enlarged, fragmentary cross-sectional view taken on the line 4-4 of FIGURE 2; and

FIGURE 5 is an enlarged, fragmentary cross-sectional view taken on the line 5-5 of FIGURE 2.

The dominant figures of my design reside in the portions shown in full lines.

I claim:

The ornamental design for a loading ramp for vehicles and the like, as shown and described.
